UNITED STATES PATENT OFFICE

2,205,296

PULPSTONE

Carl L. Leafe, Hamilton, Ontario, Canada, assignor to Norton Company, Worcester, Mass., a corporation of Massachusetts

Application March 2, 1939, Serial No. 259,401

1 Claim. (Cl. 51—207)

The invention relates to pulpstones.

One object of the invention is to prevent the wearing away of the inner concrete portions of the pulpstone just outside of the holding flanges. 5 Another object of the invention is to grind away any wood splinters that may be jammed between the stone and the frame. Other objects will be in part obvious or in part pointed out hereinafter.

10 The invention accordingly consists in the features of construction, combinations of elements, and arrangements of parts as will be exemplified in the structure to be hereinafter described, and the scope of the application of which will be indicated in the following claim.

In the accompanying drawing illustrating one of many possible embodiments of the mechanical features of this invention,

Figure 1 is an axial sectional view of a pulpstone constructed in accordance with the invention, the section being taken along the line 1—1 of Figure 2.

Figure 2 is an end elevation of the pulpstone.

Figure 3 is an elevation of a protective plate 25 which is more specifically the subject of the present invention, and

Figure 4 is a sectional view taken on the line 4—4 of Figure 3.

Referring first to Figure 1 there is therein illustrated a pulpstone which excepting for the features to be specifically pointed out is made in accordance with the disclosure in United States Letters Patent No. 1,920,204 to Thure Larsson. The protective plates of the present invention 35 may, however, be applied to other types of pulpstone, for example that disclosed in Patent 2,141,608 to Thure Larsson.

Still referring to Figure 1, the pulpstone may be mounted upon a central shaft 10 which is 40 threaded at the portions 11 and has flanges 12 to grip the stone. It has been customary for the mills to use flanges 12 which are somewhat smaller in diameter relatively speaking than those disclosed in the aforesaid Patent No. 1,920,204 to Larsson. The pulpstone further 45 consists of bonded abrasive segments or sectors 13 secured by elastic tension bolts 14 to a central steel cylinder 15. The bolts 14 are secured to the segments 13 by wedge blocks 15 which fit 50 between dove-tailed portions of the segments 13, all as described in the patent referred to. Concrete 16 is poured between the cylinder 15 and the segments 13 and forms the whole into a monolith. An inner steel hub 20 is connected to 55 the cylinder 15 by another concrete mass 21 and

centering bolts 22 are provided axially to center the stone upon the shaft 10. The foregoing is described in greater detail in the Patent No. 1,920,204 referred to and the several advantageous features thereof are fully explained therein. 5

As aforesaid the flanges 12 which are supplied by the user of the pulpstone have in many cases, for one reason or the other, been of a diameter less than that of the concrete portion 16. Since the concrete portions of the stone are much less 10 resistant to wear than the ceramicly bonded and vitrified abrasive segments 13, the concrete has been subject to abrasion due to the continual presence of grinding water with abrasive particles therein. Wood splinters become lodged between the stone and the frame of the pulp grinder and constitute a hazard and, carrying entrained abrasive as they do, increase the abrasive action upon the concrete. 15

Referring now especially to Figures 2, 3 and 20 4, I provide abrasive plates 25. These are generally segmental in shape or as actually shown constitute a five sided figure having a straight edge 26, a pair of similar edges 27 at an obtuse angle to the edge 26 and a pair of similar edges 28 substantially at right angles to the edges 27 25 with a protruding semi-circular portion 29 joining edges 28, and in the short dimension as shown in Figure 4 constituting a rectangle modified by rectangular projections 30 leaving rectangular 30 grooves 31. These plates 25 may be made of the same material as the segments 13, that is to say of abrasive bonded with vitrified ceramic bond and fired in a kiln. The abrasive may be fused alumina, emery or corundum, or silicon carbide, 35 or any other desired type. I might bond the abrasive for the plates 25 with ceramic bond, for example with synthetic resin or with rubber or sodium silicate might be used, but vitrified ceramic bond is preferred. 40

The plates 25 are located in the wheel as clearly disclosed in Figures 1 and 2 with the projections 30 extending into the concrete 16 and the concrete 16 extending into the grooves 31. In other words a set of plates 25 is placed at the 45 bottom of the stone as the concrete 16 is being poured, and when the pouring has been finished and the concrete is still soft another set of plates at the other end are placed in position. The lines 26 of the plates 25 terminate at the 50 flanges 12, that is to say the lines 26 are substantially tangent to the flanges. I prefer this construction because then the flanges will not grip the abrasive material but will rather grip the concrete and this saves wear on the flanges. 55

However in certain cases the plates 25 may extend under the flanges 12 and the flanges may grip the plates 25 and thereby a firm driving action is secured.

5 By the provision of the plates 25, wearing away of the concrete 16 is altogether eliminated and the plates 25 will last as long as the stone does because they are subjected only to incidental abrasion and not to regular grinding action. Any
10 splinters which enter between the frame and the ends of the stone will be quickly ground up and thereby removed. This eliminates hazards in operating the stone as well as reducing the wear thereof. The semi-circular projections 29
15 of the plates 25 cover the concrete which covers the ends of the wedge blocks 15.

It will thus be seen there has been provided by this invention an article in which the various objects hereinabove set forth together with many
20 thoroughly practical advantages are successfully achieved. As many possible embodiments may be made of the above invention and as many changes might be made in the embodiment set forth it is to be understood that all matter here-

inbefore set forth or shown in the accompanying drawing is to be interpreted as illustrative and not in a limiting sense.

I claim:

A pulpstone assembly comprising a central shaft, threaded portions on said shaft, internally threaded flanges screwed onto said threaded portions, a pulpstone between said flanges comprising a hollow generally cylindrical concrete center portion, a plurality of abrasive segments surrounding said concrete center portion, means securing said bonded abrasive segments to said concrete center portion, there being a gap in a radial direction between the segments and the peripheries of the flanges, and a plurality of protective abrasive plates embedded in the concrete whose surfaces are substantially in radial planes, and which collectively substantially cover the gap between the flanges and the bonded abrasive segments, constituting protective devices for the concrete and capable of grinding any wood splinters that approach the axis of the stone.

CARL L. LEAFE.
